PERCY E. PIERCE, OF ALTOONA, PENNSYLVANIA.

CARBON-COPY ATTACHMENT FOR TYPE-WRITING MACHINES.

1,149,855.

Specification of Letters Patent. Patented Aug. 10, 1915.

Application filed July 22, 1914. Serial No. 852,337.

To all whom it may concern:

Be it known that I, PERCY E. PIERCE, a citizen of the United States, residing at Altoona, in the county of Blair and State of Pennsylvania, have invented a certain new and useful Improvement in Carbon-Copy Attachments for Type-Writing Machines, of which the following is a specification.

10 To those persons familiar with the operation and utility of typewriting machines the difficulty of obtaining a reasonably large number of legible carbon copies at one writing is a well known fact. The ordinary 15 platen, or rubber roll, which is used on practically all typewriting machines, offers a more or less resilient or cushioning effect to the type bar when striking the paper, which in itself is a proper condition, if only a few 20 carbon copies of the original writing are desired, but, owing to the cushioning nature of the platen roller, the number of satisfactory carbon copies obtainable at one writing is curtailed, and usually the last sheets 25 or impresses will be dim and almost unreadable.

I have found by actual experimenting and reduction to practice that much better results, in the quantity of legible carbon copies 30 that can be obtained, will be had if the background, or surface immediately below and contacting with the last sheet of paper, were of a hard, unyieldable nature, in place of the usual yieldable rubber roll.

35 My invention therefore aims to provide a very simple and inexpensive attachment for the ordinary platen roll, whereby a reasonably large number of carbon copies can be obtained at one writing, said device being 40 easily removed from its position against the roll.

Constructively my invention involves the provision of a strip of hard, unyieldable, material, preferably of a metallic nature, to 45 occupy a position relatively longitudinal with the platen roll, which it closely engages, but does not interfere with the roll's free rotary movement. Said strip will be removably fixed in its proper position directly in the path of the type bar, which attitude will vary somewhat in different makes 50 of machines.

In the accompanying drawing I have shown one embodiment of my invention, but 55 I do not limit myself to the exact detail formation disclosed herewith, reserving the

right to make necessary alterations and amendments thereto that will conform in all respects to the original idea and intention and which will be within the scope of the 60 appended claims.

Referring then to said drawing Figure 1 is a plan of an ordinary platen roller showing the relative position of my device as associated therewith; Fig. 2 is an elevation of 65 the said roll and attachment; Fig. 3 is a cross sectional view showing relative position of the device with respect to the sheets of paper and type bar; Fig. 4 is a perspective view of the device detached from the 70 roll, and Fig. 5 shows one of the terminal securing members.

The device in itself, designated by the numeral 1, consists primarily of a single strip of hard material, preferably of spring steel, 75 of adequate length, breadth, and thickness, which, in cross section, is made concave throughout its entire length, in order to conform to the contour of the platen 2, which it closely engages when properly positioned. Said strip is made slightly bowed from end to end in order that, when the terminals thereof are secured to the frame work of the carriage, the said strip will assume a uniform bearing and close alining 85 contact with the said roll throughout its entire length. Various modified means can be employed for removably securing the said strip in operative position, said means depending on the style of machine to which it 90 is applied. In the drawing I have disclosed one practical attaching means involving the arm members 3 secured at or adjacent to the terminal ends of the strip, or these arms may be an integral part of the strip, their 95 upper free ends being bent at an approximate right angle to the main portion, to afford an adequate attaching means, when taken in conjunction with a fixed L-shaped bar 4. This latter member, as shown in Fig. 100 5, is fastened to the frame of the carriage of the machine adjacent to both housed ends of the platen roll, set screws 5' being utilized to removably connect the said arms 3 with the bars 4.

The strip 1 is suspended in front of the platen roll, with which it contacts in the manner heretofore described, but does not necessarily act as a brake or prevent said roll from being rotated in order to feed the 110 paper, nor does it interfere with the insertion and manipulation of said paper. Any

number of sheets, limited only by the maximum capacity of the paper feed mechanism, can be presented in front of the strip 1, as shown in Fig. 3, said plurality of sheets acting in themselves as a cushioning medium to the blow imparted by the type bar 6, but owing to the hard, unyieldable surface provided by said strip, as a background for the sheets of paper, a uniform impression will be made on all the said sheets, thus accomplishing the object of this invention.

By the term "unyieldable," as used throughout the specification and claims, in referring to said strip 1, is meant that the material entering into its composition is not of a resilient nature, such as rubber, but is of a sufficient hardness to be unaffected by the blow imparted by the type bar. Said strip is intended to be more or less flexible in respect to its bending qualities, for example of a nature kindred to spring steel or whale bone, but unyieldable in respect to its material composition.

What I claim as my invention is:—

1. In a typewriting machine the combination with the platen roll, of a strip of hard unyieldable material positioned in fixed longitudinal alinement against said roll, and in direct line with the striking point of each type bar, but not interfering with the roll's rotation, supporting bar members carried by the frame of the carriage of the machine, adjacent to the ends of the platen roll, and arms carried by the strip for removable locking engagement with the said bars.

2. In a typewriting machine the combination with the platen roll, of a flexible strip of hard unyieldable material, corresponding in cross section to the contour of said

roll, supporting bar members carried by the frame of the carriage of the machine adjacent to the ends of the platen roll, and arms carried by the strip for removable locking engagement with the said bars to hold said strip in suspended attitude against the said roll.

3. In a typewriting machine the combination with the platen roll, of a flexible strip of hard unyieldable material positioned in fixed longitudinal alinement against said roll, but not interfering with the roll's rotation, and in direct line with the striking point of each type bar, said strip corresponding in cross section to the contour of the said roll, and having a normal predetermined bow from end to end thereof when detached from the roll; L-shaped bar members carried by the frame of the carriage of the machine adjacent to the ends of the platen roll; and suspending members carried by the strip for removable locking engagement with the said bars.

4. In a typewriting machine the combination with the carriage and platen roll, of a flexible strip of hard unyieldable material positioned in fixed longitudinal alinement against said roll, and in direct line with the striking point of each type bar, but not interfering with the roll's rotation; and suspending members carried by the strip for removable locking engagement with the frame of the carriage.

In testimony whereof I affix my signature in the presence of two witnesses.

PERCY E. PIERCE.
